CLAIM

The ornamental design for a facial scrubbing device, as shown and described.

DESCRIPTION

FIG. 1 is a perspective view of a facial scrubbing device showing an embodiment of our new design.

FIG. 2 is a left view of the facial scrubbing device of FIG. 1.

FIG. 3 is a right view of the facial scrubbing device of FIG. 1.

FIG. 4 is a front view of the facial scrubbing device of FIG. 1.

FIG. 5 is a rear view of the facial scrubbing device of FIG. 1.

FIG. 6 is a top view of the facial scrubbing device of FIG. 1.

FIG. 7 is a bottom view of the facial scrubbing device of FIG. 1; and,

FIG. 8 is a bottom perspective view of the facial scrubbing device of FIG. 1.

The broken lines in the figures show portions of the facial scrubbing device and/or environment that form no part of the claimed design.

While the accompanying drawings include broken lines that form no part of the claimed design, the broken lines provide written description of prospective embodiments that are claimed when one or more of the broken lines are amended to solid lines. Similarly, while the solid lines in the drawings form part of the claimed design, the solid lines provide written description of prospective embodiments that are not claimed when one or more of the solid lines are amended to broken lines.
